(57) **CLAIM**

The ornamental design for surgical drape for flat panel screen displays and touch screen surgical input devices, as shown and described.

DESCRIPTION

FIG. 1 is a front perspective view of a surgical drape for flat panel screen displays and touch screen surgical input devices showing my new design with its intended environment (including a flat panel touch screen) in use;

FIG. 2 is a front perspective view thereof;

FIG. 3 is a top plan view thereof;

FIG. 4 is a front elevational view thereof;

FIG. 5 is a left side elevational view, the right side elevational view being a mirror image thereof;

FIG. 6 is a right side elevational view, the left side elevational view being a mirror image thereof;

FIG. 7 is a bottom plan view thereof; and,

FIG. 8 is a rear elevational view thereof.

It is understood that the top portion of the surgical drape for flat panel screen displays and touch screen surgical input devices consists of two layers, but because the material is thin, it is shown with a single line in FIGS. 2–8.

The broken line showing of a flat panel touch screen is included for the purpose of illustrating environmental structure and forms no part of the claimed design.
